(57) **CLAIM**

The ornamental design for a scooter deck, as shown and described.

DESCRIPTION

FIG. 1 is a top front perspective view of a scooter deck, showing my new design;

FIG. 2 is another top front perspective view thereof;

FIG. 3 is a bottom back perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The shade lines in the Figures show contour and not surface ornamentation.

The broken lines in the Figures are included to show unclaimed subject matter only and form no part of the claimed design.

1 Claim, 5 Drawing Sheets
